Patented June 17, 1919.

UNITED STATES PATENT OFFICE.

ARTHUR R. PETTERSON AND ANDREW P. WERME, OF WORCESTER, MASSACHUSETTS.

POWER-OPERATED TOOL-CASING.

1,307,146.

Specification of Letters Patent. Patented June 17, 1919.

Application filed December 2, 1918. Serial No. 265,046.

To all whom it may concern:

Be it known that we, ARTHUR R. PETTERSON and ANDREW P. WERME, citizens of the United States, both residing at Worcester, 5 in the county of Worcester and State of Massachusetts, have invented a new and useful Power-Operated Tool-Casing, of which the following is a specification.

The principal objects of this invention are 10 to provide a compact arrangement of gearing for driving a drill or other tool from a self-contained electric motor so that it can be speeded down to a practicable point and yet permit of the gearing being contained 15 with the motor in a comparatively small casing or frame; to provide such a drive in a form in which the power is transmitted through solid shafts in central alinement in the casing, to provide means for solidly supporting the shafts positively and at the 20 same time strengthen the construction; and also provide a balanced construction; to provide a construction made up of units each readily and independently removable and 25 replaceable in case of repairs are needed; to provide a maximum of interchangeable elements; to provide in coöperation therewith an oscillating valve grinder the power for 30 which is transmitted through an element constituting a bearing for the drill shaft; and to provide improvements in the means for holding the valve grinder.

Reference is to be had to the accompanying drawings in which—

35 Figure 1 is a view of half of the frame or casing with the front half removed, showing the interior parts in section taken along the plane of the edges of the half frame;

40 Fig. 2 is a sectional view on the line 2—2 of Fig. 1 looking upwardly and giving a bottom plan view of the oscillating drive and parts of the other features;

45 Fig. 3 is a side elevation of the lower part of the device showing the chuck for the valve grinder;

Fig. 4 is a similar view of the drill chuck, and

Fig. 5 is a sectional view on the line 5—5 of Fig. 1.

50 The invention is shown as comprising a frame or casing consisting of two parts 10 detachably secured together in any desired manner as by screws entering the holes 9 and each consisting of a casting having sev-

eral semi-circular webs 11, 12 and 13 cast 55 therein which when fitted together meet along their edges and constitute reinforcements for strengthening the casing and firm supports for bearings 39 for the several shafts. These bearings are non-circular outside and fit non-rotatably in grooves in the edges of the webs. There is also an end 14 at the top which supports the shaft 16 at that end of the driving motor 15. This driving shaft 16 is supported on the web 11 and 60 end 14. It has a motor pinion 17 meshing with a gear 18 on a shaft 19 which is supported in all three webs 11, 12 and 13.

On this shaft is a pinion 20 meshing with a gear 21 keyed to a central shaft 22 and 70 driving it. On this shaft is a pinion or small gear 23 meshing with a gear 24 on a shaft 25 supported in the webs 12 and 13. This shaft carries an arm 26 on the end which has a longitudinal pin 27 connected 75 by a link 28 with a head 29 on a sleeve 30. This sleeve 30 is mounted to oscillate in a bearing 31 on the lower end of the casing 10. The sleeve 30 has a bushing 32 inside it which receives the shaft 22. This shaft 80 extends through the sleeve 32 and is provided with a spindle 33 for receiving a drill chuck. This shaft is geared as will be obvious, to rotate at a high speed, say for example about 1800 revolutions per minute. The sleeve 30 is geared up to oscillate at a lower speed, as for example about 800 oscillations per minute. The lower end of the bushing 32 is provided with a flange 34 between which and a flange 35 on the drill 90 spindle are ball bearings 36.

The sleeve 30 which is positively oscillated by the gearing as indicated, is provided with two pins 37 shown as projecting diametrically to the edge of a flange 38 on 95 said sleeve which fits against the end of the frame.

When the device is to be used for operating a drill without changing the gearing above described, the drill chuck 50 is mounted on the screw 33 in an obvious manner and is driven positively. The oscillating motion can be disconnected if the valve grinder is not to be used at all by removing the gear 24 for example. Ordinarily, however, these gears will remain in position and when it is desired to use the device as a valve grinder a chuck 40 is applied. This chuck 100 105

has a space at the top for receiving the drill chuck spindle 33 and means at the bottom for securing the valve grinding tool to it and is provided with a spring-pressed ball 5 41 in a passage adapted to enter a notch of corresponding shape in the bottom of the sleeve 30 when the chuck is forced up to the right position. The top of this chuck is also provided with notches 42 adapted at the 10 same time to engage under the pins 37 so that the chuck is located by the ball 41 and driven positively by the pins 37. A screw 43 is also used to fasten the parts together in addition.

15 From this it will be seen that the usual difficulty in a motor driven drill of the portable type is avoided. This difficulty is due to the fact that on account of the usual direct drive it was possible to press the drill 20 against the work with sufficient force to stop it. By speeding the drill down this is avoided for all practical purposes and in spite of the speed change mechanism the motor shaft 16 and the drill shaft 22 are in central position 25 in the frame and in alinement with each other and are supported on rigid bearings constituting part of the frame or casing itself. Thus vibration and noise are avoided.

It will be seen also that when one half 30 casing is removed the bearings are thereby unfastened and left in position supported in the open grooves in the web of one half casing and all the mechanism is left exposed. Each shaft with its gears and bearings 39 35 constitutes an independent unit which can be lifted out separately as a whole and replaced without disturbing the others. The gears also are so designed that there are only two kinds, those of each kind being interchangeable. These are matters of great importance in practice. The webs across the casing have finished meeting edge surfaces and form pockets between them which receive any oil or grease from the bearings, 45 thus preventing it from flowing into the motor or on the commutator.

In combining the drill drive with the valve grinder drive there is no necessity for changing the former in any way according 50 to this invention and the power for the drill is transmitted through a central solid drill shaft which is supported in such a way as not to be likely to get out of alinement in practice; the necessity for adjusting a chuck 55 for a drill so as to use it for the valve grinder is avoided also, and a smooth and convenient form of chuck for the latter is provided.

Although we have illustrated and de- 60 scribed only a single form of the invention we are aware of the fact that modifications can be made therein by any person skilled in the art without departing from the scope of the invention as expressed in the claims. 65 Therefore we do not wish to be limited to all

the details of construction herein shown and described, but what we do claim is:—

1. In a device of the character described, the combination of a casing comprising two halves detachably secured together, each half having a plurality of registering webs extending thereacross and provided with registering grooves in their meeting edges, bearings mounted in said grooves, shafts mounted in said bearings and adapted to lie in their bearings on the webs of one half when the other is removed so that they can be lifted out of the grooves readily, a motor in the casing and gearing removable with said shafts for driving them from the motor. 75 80

2. In a device of the character described, the combination of a casing consisting of two halves removably secured together and each having a space therein, each half having registering webs extending thereacross at 85 points between the end walls and provided with registering grooves in their meeting edges, bearings mounted in said grooves, shafts mounted in said bearings, each shaft and its bearings and gearing fixed to the shaft constituting a unit removable and replaceable independently of the other shafts, said gearing on the several shafts meshing together. 90

3. In a device of the character described, the combination of a casing consisting of two halves removably secured together, each half having registering webs extending thereacross and provided with registering grooves in their meeting edges, bearings mounted in said grooves, shafts mounted in said bearings and adapted to lie on the webs of one half when the other is removed, each shaft and its bearings and gearing fixed to the shaft constituting a unit removable and replaceable independently of the other shafts, said shafts comprising two central shafts arranged end to end but removable independently and a side shaft receiving power from one and delivering it to the other through said gearing. 95 100 105 110

4. In a device of the character described, the combination of a casing consisting of two halves removably secured together and each having a semi cylindrical space therein, each half having a plurality of parallel semi-circular registering integral webs extending thereacross, and provided with longitudinal registering grooves in their straight meeting edges, each groove being in longitudinal alinement with a groove on the next web, flanged bearings removably but non-rotatably mounted in said grooves, parallel shafts mounted in said bearings and adapted to lie on the webs of one half when the other is removed so that they can be lifted out of the grooves with their bearings, a motor in the casing at one end, and interchangeable gearing removable with said shafts for driving them from the motor. 115 120 125 130

5. A casing for the purpose described consisting of two halves detachably connected together, each half having end walls provided with grooves for bearings and also 5 having cross webs inside dividing it into a plurality of separate pockets for holding oil draining from the bearings, said webs having grooves constituting means for supporting bearings, the edge of each web of one 10 half abutting against the edge of a web of the other half throughout the length thereof so as to form firm supports and hold the bearings tightly in position, seal up said pockets, and strengthen the casing.

15 6. The combination with a portable frame for the purpose described constructed in the form of a hollow casing, of a motor centrally located therein at one end and having a central longitudinal driving shaft, a second 20 central shaft in said casing in central alinement with the motor shaft, said casing having integral rigid webs affording central bearings for said shafts in alinement with each other, and gearing in the frame for 25 driving the central second shaft from the motor shaft at a reduced speed.

7. The combination with a portable frame for the purpose described constructed in the form of a hollow casing, of a motor centrally 30 located therein at one end and having a central longitudinal driving shaft, a second central shaft in alinement with the motor shaft, said casing having rigid central bearings for 35 said shafts in alinement with each other, gearing in the frame for driving the second shaft from the motor shaft at a reduced speed, said gearing being located on one side of said shafts, gearing located on the other side of said shafts opposite the first named 40 gearing and connected with the first named gearing for producing an oscillatory motion, and a sleeve supported by said casing at the end opposite the motor, and connected with the oscillating gearing to be oscillated there- 45 by and constituting a bearing for said second shaft.

8. The combination with a portable frame for the purpose described, of a motor located therein and having a driving shaft, a second 50 shaft, gearing for driving the second shaft from the motor shaft at a reduced speed, gearing connected with the first named gearing for producing an oscillatory motion, and a sleeve supported by said casing at the end 55 opposite the motor, and connected with the

oscillating gearing to be oscillated thereby and constituting a bearing for said second shaft.

9. The combination with a portable frame for the purpose described constructed in the 60 form of a hollow casing, of a motor centrally located therein, a shaft in alinement with the motor shaft, gearing in the frame for driving the shaft from the motor at a reduced speed, said gearing being located on one side of said shaft, gearing located on the other side of said shaft and connected with the first named gearing for producing an oscillatory motion, a sleeve supported by 65 said casing at the end opposite the motor, and connected with the oscillating gearing to be oscillated thereby and constituting a bearing for said shaft, the shaft projecting beyond the sleeve, and means on the end thereof for receiving a drill chuck, the sleeve 70 having readily detachable means for connecting it with a valve grinder chuck.

10. The combination with a portable frame for the purpose described, of a motor having a shaft, a second shaft, means for 80 driving the second shaft from the motor shaft at a reduced speed, a sleeve supported by said casing at the end opposite the motor, means for oscillating the sleeve from the motor at a lower speed, said sleeve constituting a bearing for said second shaft, the second shaft projecting beyond the sleeve and having a drill chuck spindle thereon, and the sleeve having readily detachable means 85 for connecting it with a valve grinder chuck, a valve grinder chuck having a space therein for receiving the end of the drill chuck spindle, spring-pressed means for locating the valve grinder chuck on the sleeve, and positive means for driving it from the sleeve. 90

11. The combination with a portable frame for the purpose described, of a motor, a sleeve supported by said casing at the end opposite the motor, means for oscillating the sleeve from the motor at a low speed, said 100 sleeve having readily detachable means for connecting it with a valve grinder chuck, a valve grinder chuck, spring-pressed means for locating the valve grinder chuck on the sleeve, and positive means for driving it 105 from the sleeve.

In testimony whereof we have hereunto affixed our signatures.

ARTHUR R. PETTERSON.

ANDREW P. WERME.
